UNITED STATES PATENT OFFICE.

LOUIS M. POTTS, OF HIGHWOOD, NEW JERSEY, ASSIGNOR TO WESTERN ELECTRIC COMPANY, INCORPORATED, OF NEW YORK, N. Y., A CORPORATION OF NEW YORK.

PRINTING TELEGRAPHY.

Application filed December 29, 1922. Serial No. 609,579.

To all whom it may concern:

Be it known that I, LOUIS M. POTTS, a citizen of the United States of America, residing at Highwood, in the county of Bergen, State of New Jersey, have invented certain new and useful Improvements in Printing Telegraphy, of which the following is a full, clear, concise, and exact description.

10 This invention relates to printing telegraphy, and particularly to a printing telegraph receiving mechanism wherein the message is recorded in printed characters in page form.

15 Its object is a printing telegraph receiving mechanism which is simple, reliable and efficient in operation and one which is inexpensive to manufacture.

20 The invention disclosed in the accompanying drawings embodies a printing telegraph receiving printer commonly referred to as a page printer, comprising selecting mechanism, a stationary paper platen and a type wheel movable transversely of the printer 25 and arrested in a printing position by the alignment of elements controlled by the selecting mechanism to form a rigid stop.

25 The invention in its preferred form provides a mechanical distributor for translating the line current impulses into mechanical movements to position suitable selecting mechanism in accordance with the line current impulses. The selecting mechanism preferably consists of a series of rotatable discs having apertures or openings therein, each opening being provided with a loosely fitting spherical member or ball. The openings in the discs and balls carried thereby are so arranged that for any given arrangement or permutation of the rotatable discs a series of balls, and only one series, will be brought into alignment to form a rigid operating connection or stop. The positions of the selecting mechanism, that is, the discs, 40 are controlled by the mechanical distributor, which, in accordance with the preferred form of the invention, comprises a plurality of revolvable and horizontally movable members, the rotation of which is controlled by a device having a natural period of motion. Each of these members is arranged to occupy either of two positions as determined by the energization of a single electromag-

net, which responds to line current impulses. Secured to each of these members is a cam 55 which engages operating elements associated with the discs for effecting the movement of the discs in accordance with the position of the selecting members. Arranged to be arrested by the forming of the 60 rigid connection or stop due to the alignment of the balls in the disc is a circular member which carries two balls and which is mounted on the normally rotating shaft. Also secured to this shaft and rotatable 65 therewith is a type wheel, on the periphery of which are two rows of characters. When the balls in the rotatable member engage those of the discs the type wheel is positioned to bring the desired character into 70 a printing position. Following the positioning of the type wheel a printing hammer operated mechanically is caused to move the paper into engagement with the desired character of the type wheel. The auxiliary 75 functions such as line feed, spacing, carriage return, shift and unshift are in each case performed mechanically, as will be described more in detail hereinafter.

80 A better understanding of the type of apparatus which forms one embodiment of this invention may be had from the following description when taken in conjunction with the accompanying drawings wherein Fig. 1 is a plan view of the receiving printer with the cover removed; Fig. 2 is a front elevation of the printer shown in Fig. 1; Fig. 3 is an end elevation of the same mechanism; Fig. 4 is an end elevation opposite to that of Fig. 3; Fig. 5 is a sectional view showing a portion of the mechanism; Fig. 6 is another sectional view taken along the broken line 6-6 of Fig. 1; Fig. 7 is a detailed view showing portions of the operating mechanism; Fig. 8 is a detailed view 85 showing the manner of construction of the printing mechanism; Fig. 9 is a detailed view showing the manner in which the mechanism for the auxiliary functions is selected; Fig. 10 is a detailed view of the mechanism shown in Fig. 9; Fig. 11 is a sectional view representing the manner in which the type wheel is shifted to bring the two rows of characters into printing position; Fig. 12 is a detailed view of the mechanism shown in Fig. 11; Fig. 13 is a detailed 90 view 95 100 105 110 115 120 125 130 135 140 145 150 155 160 165 170 175 180 185 190 195 198

view of the distributing mechanism; Fig. 14 shows the single electromagnet with its armature, which according to its position deflects the selecting elements of the distributing mechanism to one side or the other of a stationary locking vane; Fig. 15 is a detailed view of the mechanisms of Figs. 13 and 14; Fig. 16 is a development of the discs showing the arrangement of the balls carried thereby; Fig. 17 is a study view showing the different positions assumed by the selecting elements of the distributing mechanism which are rotated through the action of a balance and escapement mechanism; Fig. 18 is a detailed view showing the manner in which the discs carrying the spherical members or balls are held; Fig. 19 illustrates the elements of Fig. 18 in the other of their operative positions; Fig. 20 is a detailed view of the friction clutch with its releasing mechanism; Fig. 21 shows the manner in which the friction clutch elements of Fig. 20 are released; Fig. 22 shows the manner in which the shaft upon which the platen is mounted is prevented from being rotated in a backward direction; Fig. 23 illustrates the manner in which the printing mechanism is prevented from moving the paper into engagement with the type wheel when the auxiliary functions are selected.

The mechanism herein disclosed is operated preferably by various combinations of five positive and negative selecting impulses with an additional impulse preceding each group of character selecting impulses for releasing the distributing mechanism for operation. The impulses may arrive over a line from a distant station at which there is located suitable transmitting mechanism and pass through the windings of a single selecting magnet which responds to such line current impulses for effecting the setting of suitable distributing mechanism. This distributing mechanism being of a type suitable for translating the effects of the line current impulses into mechanical movements causes the positioning of selecting mechanism to select the desired character as determined by the group of impulses transmitted over the line conductor. Instead of employing various combinations of positive and negative selecting impulses it is contemplated that the mechanism may be operated by combinations of units of current and no current. When employing units of current and no current one of the windings of the single selecting magnet may be made inert and a retractile spring provided on the armature for restoring it to a normal position. It is to be noted, however, that when the mechanism is operated on a system wherein the selecting impulses consists of positive and negative current impulses it is necessary that a relay be inserted between the line and the single selecting magnet of

the printer for controlling the operation of the two windings of the selecting magnet forming a part of the printer.

In the accompanying drawings there is shown a stationary paper platen, a rotatable and a horizontally movable type wheel and a printing mechanism which moves in unison with the type wheel. The type wheel and printing mechanism are each mounted on a helical screw shaft, while the former is rotatable yet horizontally movable with a shaft which has power communicated thereto through a friction clutch from a continuously rotating motor. The type wheel and the printing mechanism are adapted to be moved from left to right transversely of the machine against the tension of springs one character space at each operation of the printing mechanism except when the auxiliary functions are being performed, at which time it is desired to prevent printing. Both the type wheel and printing mechanism are adapted to be released and returned to their initial position by said spring for commencing a new line of character printing. For positioning the desired character into alignment with the printing mechanism, suitable selecting mechanism, which is simple and reliable in operation, is provided.

The receiving printer illustrated in the drawings is shown in combination with the keyboard transmitter, which comprises a series of key levers 1, a plurality of permutation bars 2 and a single contact 3, which is operated in accordance with the positioning of the permutation bars 2 by the key levers 1. A keyboard transmitter of this character is disclosed in the patent to Harry Pfannenstiehl, No. 1,545,276, granted July 7, 1925.

Referring to the drawings, and particularly to Figs. 1, 13, 14 and 17, it is seen that the distributing mechanism consists of five selecting rods 7, 8, 9, 10 and 11, which are concentrically arranged about a portion of the circumference of the shaft 12. The shaft 12 is arranged to be rotated by power communicated thereto from a motor under control of a balance and escapement mechanism through a friction clutch. This balance and escapement mechanism comprises escapement wheels 13 and 14 fixed on the shaft 12, an anchor 15, a balance wheel 16, a spiral spring 17 and an impulse pin 18 which is fixed in the balance wheel 16. The helical spring 17 has one end fixed to the frame of the machine, while the other end is fastened to balance wheel 16. Pin 18 is positioned in a manner such that upon the rotation of the balance wheel 16 by the power stored in the helical spring 17, it engages a bifurcated portion of the anchor 15 for imparting to the escapement wheels 13 and 14 corresponding movements. Accordingly, shaft 12 is caused to move step by step. The movement

of the shaft 12 through the action of the balance and escapement mechanism is so timed that the selecting elements 7, 8, 9, 10 and 11 will be brought into operative relation with an armature 25 of a selecting magnet 26 upon the receipt of the line current impulses. The armature 25 of the selecting magnet 26 has its free end beveled for the purpose of deflecting vertically projecting portions of the selecting rods 7 to 11, inclusive, to one side or the other of a stationary locking vane 24 in accordance with the energization of the electromagnet 26.

10 portions of the selecting rods 7 to 11, inclusive, to one side or the other of a stationary locking vane 24 in accordance with the energization of the electromagnet 26.

15 The escapement wheels 13 and 14 have three equal stops and a fourth stop of twice the length. As the balance swings, shaft 12 takes five steps with equal time intervals between their beginnings. At the end of the sixth interval, however, the balance locks but 20 the shaft 12 continues to move on account of the long space after the third tooth. Each signal is made up of a starting impulse and five code impulses and a stop or separating impulse; seven in all. The time interval for 25 the start and stop impulses made up of the time of the long step, magnet operating time and the time for the balance to release the anchor. These factors are so proportioned with respect to the speed of the motor that 30 the start and stop intervals equal the code intervals and substantially a seven equal unit signal is the result.

35 The feature just described permits the operation of sending and receiving machines on the same circuit at the same speed since it automatically compensates for both plus and minus speed variations in either sender or receiver. In the usual stop distributors which move with uniform motion from 40 starting to stopping positions some provision must be made to insure that the receiver always finishes its cycle before the sender. This may be done by causing the sender to always stop between succeeding 45 signals or by insuring that the receiver always runs faster than the sender. In the present device the balance locks before the escapement wheels and is ready to start at the correct time for the next signal even 50 though the escapement wheel has not yet come to rest. The first stop interval of the escapement wheel then automatically shortens sufficiently to permit escapement wheel to catch up with the balance so that the receiving 55 balance may have a slower rate than the sending balance without interfering with the operation. This characteristic of the device permits the mounting of the sending distributor on the same shaft as the receiving distributor and also the use of the same clutch, release mechanism and time device.

60 The balance and escapement mechanism, which is more clearly shown in Figs. 6 and 15, is released for operation upon the receipt of a starting impulse. With the arma-

ture 25 of the electromagnet 26 in its normal position, a member 27 is positioned such that a stop arm 28 is moved so that its free end is in the path of a notch formed in the balance wheel 16. It is thus seen that when 70 the armature 25 is in its normal position, the balance wheel 16 is prevented from rotating due to the engagement of a notch therein with stop arm 28. However, upon the receipt of the starting impulse, the restraint on the member 27 is relieved and stop arm 28 through the action of a retractile spring is moved out of the path of the notch in the balance wheel 16, and accordingly the 75 balance wheel 16 is free to rotate under the action of the spiral spring 17.

80 Secured to each of the selecting rods 7 to 11, inclusive, rotatable and horizontally movable therewith is an operating cam which serves to translate the effects of the line current impulses into mechanical movements. These cams have been designated by the numerals 29, 30, 31, 32 and 33. As is apparent from Fig. 17, the selecting rods 7 to 11, inclusive, are moved step by step, and accordingly these rods will be positioned sequentially to one or the other of their operating positions. Consequently the cams 29 to 33, inclusive, will take a position corresponding to the position taken by the selecting rods individual thereto. These cams, although being positioned sequentially, are arranged so that their raised portions come in contact with associated members simultaneously. This feature permits of the setting of the selecting mechanism controlled by these cams simultaneously rather than sequentially as the selecting rods are positioned.

100 The selecting mechanism, as shown in Figs. 1, 2 and 16, consists of five discs 40, 41, 42, 43 and 44, each being provided with two rows of openings or apertures in which there are loosely fitted spherical members or balls 45. These balls 45 are arranged upon the movement of the discs to be brought into alignment for forming a rigid operating connection. In order to permit the easy movement of the discs with their associated balls, and also to permit the balls to more quickly break down the connection, plates 46 and 47 are also provided with spherical members or balls coinciding with those in the five selecting plates, which are arranged on opposite sides of the plates. It is to be noted, however, that these plates 46 and 47 110 are stationary.

115 Arranged in operative relation to the discs are five pull bars 50, 51, 52, 53 and 54. Each of these pull bars has one end bifurcated, while the other end has a projecting portion on the under surface of its free end. This projecting portion is adapted to be fitted in a notch cut in the discs so that upon the movement of the pull bar the corresponding 120 125 130

disc will be moved to one or the other of its operating positions. As shown in Figs. 18 and 19, the pull bar 50 has pivoted thereto two operating members 56 and 57, the latter having a portion surrounding an arm of the former whereby for certain positions of the latter the former will be moved in accordance with such position. The member 56 is provided with a hooked portion and a straight portion, each of which is adapted to be moved upon the positioning thereof by a universal member 58. This universal member is rotatably mounted on a rod 59 and extends across a portion of the back of the machine. The universal member 58 has a projecting portion fitted in the bifurcated end of a pivoted anchor 60. This anchor 60 is moved upon the engagement of a cam 63 mounted on a shaft 64 with the projecting portions thereof. The cam 29, 30, 31, 32 and 33 are positioned just below the members 56 and 57 so that upon the selection of these cams through the positioning of the rods 7 to 11, inclusive, and upon their continued rotation the members 56 and 57 will be moved to cause the positioning of the member 56 so that the pull bar associated therewith will be moved, and consequently this disc associated therewith will also be moved. It is to be understood, of course, that the movement of the pull bars by the movement of the universal member 58 is brought about at a time just following the positioning of the members 56 and 57 by the cams 29 to 33, inclusive.

As previously stated, the characters are formed in two rows on a type wheel 70 which is rotatably mounted yet horizontally movable on a shaft 71. Secured to this shaft is a plate 72, which, as shown in Fig. 6, has two apertures in which there are loosely fitted spherical members or balls 73 and 74. As will be described more in detail hereinafter, the shaft 71 has power communicated thereto from a continuously rotating motor through a friction clutch. Accordingly, the shaft 71 normally tends to rotate, the release of which is brought about following the positioning of the selecting elements 7 to 11. Assume now for the sake of clearness that the shaft 71 is rotating and that the discs 40 to 44, inclusive, have been positioned such that a series of balls 45 are aligned to form a rigid operating connection. Thus, upon the continued rotation of the shaft 71 and the plate 72 one or the other of the balls 73 and 74 will engage the aligned balls. The engagement of either of the balls 73 and 74 with the aligned balls causes the shaft 71, and consequently the type wheel 70, to be stopped. The type wheel 70 will be stopped in a position such that the desired character is in alignment with the printing mechanism.

The printing mechanism comprises a

printing hammer 75 which is operated mechanically through a series of links or levers for moving the paper 77 into engagement with the character on the type wheel 70 positioned in the manner previously described. Ink for the type wheel 70 is provided by an inking roll 78 suitably mounted on the type wheel carriage, while the paper 77 is supplied from a roll 79 which passes around a platen 80.

70
75

Distribution of power.

Referring particularly to Figs. 1, 2, 3 and 4, there is shown a motor 80 which has its driving shaft coupled with a shaft upon which is secured a driving gear 82 by means of a flexible coupling 81. The driving gear 82 drives an intermediate gear 83, which has associated therewith a reduction gear 84. The teeth of the reduction gear 84 mesh with those of gear wheel 85 secured at one end of shaft 64. The shaft 64 extends across the back of the machine and has secured on its end opposite to the one carrying the gear wheel 85, a gear wheel 86, which has associated therewith a friction clutch. This latter feature is clearly shown in Fig. 20. The teeth of the gear wheel 86 mesh with those of an idler gear 87 mounted loosely on shaft 88. The shaft 88, like shaft 64, extends across the machine and serves as a support for the platen about which the paper 77 passes. The teeth of the idler gear 87 mesh with the teeth of a second idler gear 89 mounted on a rod 90, which also serves as a means for securing the stationary plates 46 and 47 in position. The idler gear 89 drives a gear 91, which is secured to the shaft 71, which like the shaft 64 is driven through a suitable friction clutch as is more clearly shown in the lower left hand portion of the apparatus of Fig. 1.

The construction of the friction clutch is as follows: mounted on the side of the gear wheel 86 is a series of posts 92 on which are mounted a plurality of plates 93 adapted to rotate with the gear wheel 86. Rigidly secured to a sleeve 65 which surrounds a portion of shaft 64 and which has secured thereto the operating cams, is a plurality of plates 94 which are of lesser diameter than the plates 93. Intermediate the plates which are rigidly secured to the gear wheel 86 and the plates 94 which are rigidly secured to the sleeve 65 is a series of friction discs 95 which may consist of wood or any desirable material. Mounted on a sleeve surrounding the power shaft and directly coupled with the friction clutch just described is a stop member 96, which is normally engaged by a projecting portion of a pivoted member 97. Accordingly, the pivoted member 97 prevents the stop member 96, together with the elements of the

100
105
110
115
120
125
130

friction clutch, from rotating. There is also associated with the pivoted member 97 a cam 98, the cam 98 being rigidly secured to the shaft 12 about which the selecting elements 7 to 11, inclusive, are arranged and which rotate with this shaft. The cam 98 has its depressed portion arranged such that the pivoted member 97 under the action of a retractile spring will be caused to move 5 inwardly, thereby moving an end of the pivoted lever out of the path of the stop member 96. The stop member 96 with its associated mechanism is thereupon free to rotate by power communicated thereto from the friction clutch. It is apparent from the preceding description that power is communicated from the continuously operating motor 80 through suitable gearing to a friction clutch and then through other gears 10 to the shaft upon which the type wheel 70 is mounted.

A better understanding of the invention may be had from a description of a particular character selection and the various 15 operations incident thereto.

Let it be assumed that the sending apparatus at a distant station is transmitting a series of impulses for selecting the character D, and let it be further assumed that the character D is selected by five units combined in the following order: positive, negative, negative, positive and negative; or it may be assumed also that the five selecting units are represented by current, no current, 20 no current, current and no current. It is, of course, to be understood that since the mechanism herein described is of the start-stop type, it is necessary that the selecting units be preceded by a current impulse for effecting the release of the distributing mechanism. Also let it be assumed that for the particular selection chosen for illustration that the left hand winding of the electromagnet 26, considered from the back of the machine, is energized upon the receipt 25 of a positive impulse while for a negative impulse the right hand winding is energized.

The transmission of a starting impulse causes the energization of the electromagnet 26 for releasing the support of the member 27 and thus permitting stop arm 28 to release under spring tension. The balance wheel 16 is now free to rotate by the action of the spiral spring 17. The escapement wheels 13 and 14 will for each oscillation of the balance wheel 16 through the action of the pin 18 be caused to advance one step at a time. The shaft 12, which is driven through a friction clutch under control 30 of the balance wheel through the anchor and escapement wheels, has imparted thereto a corresponding movement. As shown in Fig. 17, for each oscillation of the balance wheel the escapement wheels will be moved to assume a different position, which in turn

causes the rotation of the selecting elements 7 to 11 in a step by step fashion. As the selecting elements 7 to 11 are rotated in this manner and upon their engagement with the armature 25 of the electromagnet 26, they 35 will be deflected to one side or the other of the stationary vane 24 in accordance with the character of the line current impulse or the selecting unit. For the particular selection chosen the vertical projecting portions 40 on the selecting elements 7 and 10 will be deflected to the left of the stationary vane 24 upon being brought into engagement with the armature of the electromagnet 26, while for the other selecting units the vertical 45 projecting portions of the selecting elements 8, 9 and 11 will be deflected to the right of the stationary vane upon their continued rotation. The positioning of the selecting elements in this manner causes the 50 corresponding positioning of the cams 29 to 33.

Following the positioning of selecting element 11, the depressed portion of cam 98 is brought into alignment with the upper 55 portion of the pivoted lever 97 which is now moved under the action of a retractile spring to a position such that the stop member 96 is free to rotate. Power is now communicated to the sleeve 65 through the friction clutch and the connecting gear from the motor 80. Consequently, a continuous motion is imparted to the sleeve 65, upon which there is mounted a number of cams for performing the necessary mechanical operations.

The positioning of the cams 29 to 33 by the movement of the selecting elements 7 to 11 to the positions just described causes, upon the continued rotation of these cams, the 60 operation of the elements 56 and 57 which are secured to each of the pull bars 50 to 54, inclusive. For the particular selection chosen the cams 29 to 33, inclusive, act on the pivoted elements 57 of the pull bars 50 and 53, respectively, while the other of the cams act on the pivoted element 56 of the pull bars 51, 52 and 54, respectively. As the sleeve 65 continues its rotation, cam 63 is 65 brought into operative relation with the operating elements of the pivoted anchor 60, whereupon the universal member 85 is rotated for moving the pull bars 50 to 54, inclusive, in accordance with the positioning of the cams 29 to 33, inclusive. The movement 70 of the pull bars 50 to 54, inclusive, causes the rotation of the discs 40 to 44 to a position such that one series, and only one series 75 of the spherical members or balls carried thereby are aligned to form a rigid operating connection. For the purpose of illustration it may be assumed that the discs are moved to a position such that the balls are aligned in the manner shown in Fig. 16.

As previously stated, the shaft 71 upon

which the type wheel 70 is mounted has imparted thereto power through the idler gears 87 and 89 from the driving gear 86. Accordingly, this shaft is continuously rotated so long as the pivoted lever 97 is out of the path of the stop member 96 and the balls in the circular plate 72 have not engaged any of the balls in the selecting discs 40 to 44, inclusive. The type wheel with its associated shaft thus continues its rotation until the ball 73 carried by the plate 72 engages the aligned balls, at which time the type wheel is arrested for bringing the character D into alignment with the printing mechanism. It is to be noted here that the shaft 71, as previously stated, is driven from the gear wheel 97 through a friction clutch and is thus capable of being arrested without causing the stoppage of the other gears.

Just following the positioning of the character D in alignment with the printing mechanism, cam 110, which is mounted on the sleeve 65, has its depressed portion brought into alignment with the bell crank lever 111. The bell crank lever 111 is rotatably mounted on a shaft 112 and through links 114 and 115 a movement corresponding to that of bell crank lever 111 is imparted to shaft 116. As shown in Figs. 4 and 7, the shaft 116 has secured thereto a bell crank lever 116 which serves to move the free end of a pivoted member 117 into engagement with teeth in a toothed wheel or gear 118. The gear 118 is secured on one side of the type wheel 70, the number of teeth corresponding to the number of characters on the type wheel. The engagement of the free end of the pivoted member 117 with the teeth in the gear wheel 118 causes the type wheel 70 to be positioned such that the character D is correctly aligned with the printing mechanism. The restoration of the pivoted member 117 to the position shown in Fig. 4 is brought about when the raised portion on the cam 110 engages the free end of the bell crank lever 111.

Referring now to Fig. 8, there is shown a cam 76 secured to sleeve 65, which is now being rotated by power from the motor 80. The cam 76 is arranged on the sleeve 65 in such a manner that its depressed portion is brought into alignment with a pivoted lever 100 following the positioning of the type wheel to bring the desired character into a printing position. The pivoted lever 100 acts on a connecting lever 101, which has its other end connected with a lever 102 secured to shaft 103. As the pivoted lever 101 is moved downwardly under the action of a retractile spring shaft 103 is caused to rotate through the linkage arrangement just described for producing a rotative motion to an element 104, the bifurcated end of which moves a printing hammer 75 through the in-

strumentality of a pin 105 to move the paper 77 into engagement with the aligned type. Consequently, the character D will be printed on the paper 77.

70 Spacing.

Spacing between characters is effected by the power shaft, and in the embodiment disclosed the type wheel and the print mechanism are moved forward one step or one 75 character space against the tension of a spring 119 immediately after each character is printed. Rotatably mounted on shaft 88 is a ratchet wheel 120, the teeth of which are adapted to be engaged by an operating pawl 80 121 and a holding pawl 122. The operating pawl 121 is secured on one side of a rotatable member 123, the movement of which is produced upon the rotation of a link 124, which has its free end fitted in the bifurcated end of the member 123. As shown in Fig. 5, the link 124 is rigidly secured to the shaft 103. As previously stated, shaft 103 is rotated when the depressed portion of cam 76 is brought into alignment with the 90 free end of member 100, whereupon the printing hammer 75 is moved through a series of links to effect the printing of the desired character. At the same time, the link 124 is rotated for causing the stepping pawl 121 to be moved to the right for engaging the next succeeding tooth. When the member 100 again engages the raised portion of cam 76, shaft 103 is rotated to the 95 position shown in Fig. 8, at which time link 124 is moved to the position shown in Fig. 5, and accordingly ratchet wheel 120 is advanced a distance equal to the space of one tooth.

In order that the movement of the ratchet 105 wheel 120 will be imparted to the shafts upon which the carriages supporting the type wheel and the printing mechanism are located, the gear wheel 125 is secured to the ratchet wheel 120. The teeth of the gear 110 wheel 125 engage those of a driving pinion 126, which has its teeth meshed with those of gear wheels 127 and 128. These latter gear wheels are secured to one end of spiral screw shafts 129 and 130, respectively, upon 115 which the type wheel and printing mechanism carriages are mounted. Thus, for each movement of the ratchet wheel 120, a corresponding movement is imparted to the shafts 129 and 130 for moving the respective carriages a distance determined by the advancement of the operating pawl 121. As shown in Figs. 1 and 2, shafts 129 and 130 are each provided with spiral screw portions, on the inner surfaces of which there 120 is arranged a pair of rollers to which is secured the respective carriages. The provision of these rollers permits the movement of the carriages without appreciable friction. Although the preceding description 125 130

states that the type wheel and the printing mechanism are spaced ahead immediately after a character is printed, it is obvious that spacing may be effected, if desired, immediately preceding the printing of each character.

When it is desired to space between words, the spacing is effected in the manner above described, but the distance through which the printing hammer is allowed to travel is reduced to a point such that the paper is not caused to engage the type wheel. Consequently, the printing of characters, when such function is desired, is prevented.

Auxiliary operations.

In addition to selecting and printing various characters and providing means for spacing between characters and words, as hereinbefore described, there are various auxiliary mechanical operations to be performed, such for example, as carriage return, line spacing, shift and unshift, that is, shifting from upper case to lower case and vice versa.

To the left hand side of Fig. 1 is shown a plurality of special pull bars 131, 132, 133, 134 and 135, which are horizontally movable and each of which has secured thereto a vertically extending link such as 136. As shown in Fig. 10, each of these pivoted links has a portion in alignment with an operating pin 137. Each of these pins, there being five in number corresponding to each of the pull bars 131, 132, 133, 134 and 135, is individual to a series of auxiliary spherical members 138 and 139, which are arranged in the discs 40 to 44 on the arc of a circle, the diameter of which is slightly greater than the diameter of the circles upon which the series of balls 45 are arranged. Positioned just below the auxiliary series of balls are variously shaped notches in which the free ends of the links 136 are arranged to be moved. For moving the pull bars in accordance with their selection as determined by the alignment of the auxiliary series of balls in a manner similar to that previously described in connection with the selection of the character D, a universal bar 140 is provided. This bar 140 has one end pivoted, while its free end is arranged to engage a notch cut in each of the pull bars 131, 132, 133, 134 and 135 upon its movement into the notches of the discs 40 to 44, inclusive. The notches on the edges of the discs 40 to 44, above referred to, have cam faces on one side or the other of the notches, depending upon whether the disc is in the set or normal position for the function with which that notch is associated. When the discs are all in the position for function, the levers 136 are free to move into the notches. If any one of the five

disks is moved to its other position, the cam faces return lever 136 to normal. It will thus be seen that lever 136 is moved with substantially a positive motion in both directions as the disc shifts. The universal bar 140 is connected with an eccentric 141 mounted on sleeve 65 by a connecting rod 142. The eccentric 141 is positioned on the sleeve 65 such that the rod 142 and the universal bar will be moved following the selection of the pull bars 131 to 135, inclusive.

It will be understood, of course, that the pull bars 131, 132, 133, 134 and 135 are selectively controlled by line current impulses in substantially the same manner as that described in connection with the positioning of the type wheel, that is, the various auxiliary mechanical functions are selectively controlled by both positive and negative impulses which are transmitted in the same manner and by the same means as the various character selections. The power for performing these functions is also supplied from the motor 80, which imparts its motion to sleeve 65 through a friction clutch, a part of which is mounted on shaft 64.

Line feed.

For the purpose of rotating the platen 80 to feed the paper and space between lines or printed characters, a link 143 extending from a bell crank lever 144 and the pull bar 132 is provided. The bell crank lever 144 is rotatably mounted on shaft 88 and carries an operating pawl 145 on the end opposite to that to which the link 143 is connected. The operating pawl 145 is arranged to engage the teeth of a ratchet wheel 146 rigidly secured to shaft 88 upon which the platen is mounted.

When the auxiliary spherical members 138 are aligned to form a rigid operating connection, pin 137 corresponding to pull bar 132 causes the movement of this pull bar upwardly such that the notch therein is in alignment with the end of the universal bar 140. When the sleeve 65 reaches a position such that the eccentric 141 is effective, the universal bar 140 is moved outwardly for causing the corresponding movement of pull bar 132. The movement of the pull bar 132 outwardly produces a like movement to link 143, whereupon the operating pawl 145 rotates the ratchet wheel 146. Accordingly, the shaft 88 and the platen 80 are rotated to a position such that an unprinted area of the paper is presented before the type wheel and printing mechanism.

In order that there shall be no back lash in the movement of the shaft upon which the platen is mounted, a ratchet wheel 147 is secured on the extreme right hand side of this shaft. This ratchet wheel 147 is arranged to be engaged by a projection carried

by a jockey spring 148, whereupon the ratchet wheel 147 together with the shaft 88 will be prevented from being rotated in a direction opposite to that of its forward movement.

When the auxiliary operations of the printed are being performed it is highly desirable that the printing mechanism, and in many cases the spacing mechanism, be prevented from operating. According to the preferred form of the present invention there is secured to the shaft 71 upon which the type wheel 70 is mounted a sector 150. The sector 150 is arranged with respect to the type carried by the type wheel 70 such that when any one of the auxiliary pull bars 131 to 135, inclusive, is selected it will be in a position such that the printing hammer 75 and the spacing mechanism are prevented from operating. As shown in Figs. 8 and 23, forming a part of the operating lever 100 is an extending lever 151 which is arranged to engage the surface of the sector 150 when the type wheel is positioned such that the sector 150 is in alignment with the projecting portion of the extending member 151. The printing hammer and the spacing mechanism are prevented from going to their fullest extent, thereby preventing them from performing their allotted functions. The sector 150, however, is provided with a depressed portion which permits the spacing pawl to be moved to a position such that it engages the next succeeding tooth but which prevents the printing hammer 75 from causing the engagement of the paper 77 with the type carried by the type wheel. This particular position is shown in full lines in Fig. 23, while the dotted lines indicate a position of this lever for the other auxiliary selections. It is apparent from the previous description that for each of the auxiliary function the printing mechanism and the spacing mechanism are prevented from operating, while in the case of spacing between letters and words the spacing mechanism is permitted to operate while the printing mechanism is prevented from causing the engagement of the paper with the type of the type wheel.

Shift.

As previously stated, the type wheel 70 is provided with two rows of characters, one of which carries the letters while the other carries figures, punctuation marks and other special characters. Normally, the screw shaft 130, the rotation of which translates to the type wheel by a step by step motion, is normally under spring tension of a spring 153 which is secured between a supporting member 154 and a thrust bearing 155, the latter being in engagement with a surface of the gear wheel 128 carried by the shaft 130.

Also secured to the shaft 130 is a collar 156,

which has arranged therewith a thrust bearing 157. As shown in Figs. 11 and 12, there is provided a pivoted member 158 which is normally under spring tension and which holds the shaft 130 against the tension of the spring 153 in its unshifted position.

When it is desired to shift the type wheel, that is, bring the row of figures, punctuation marks and other special characters in alignment with the printing mechanism, it is necessary that the selecting rods 7 to 11 be positioned in accordance with the predetermined code combination of impulses allotted to this particular function. The positioning of the selecting elements 7 to 11, inclusive, produces through the cams 29 and 33 movement of the discs 40 to 44, inclusive, such that the auxiliary series of balls 138 or 139, as the case may be, cause the pin 137 individual to the pull bar 135 to be selected. The selection of this pin moves the pull bar 135 to a position such that its notched portion is in alignment with the universal member 140. Thus, upon the movement of the universal member 140 by the action of the eccentric 141 on the operating arm 142, the pull bar 135 is moved to a position such that operating member 160, Fig. 12, is moved to cause a corresponding movement of the connecting link 159 which is fixed to the operating member 160 and the pivoted member 158. When the pull bar 165 is moved in this manner the pivoted member 158 under the action of its retractile spring is moved to a position such that the member 158 is moved away from the collar 156, whereupon the shaft 130 and the type wheel 70 are allowed to move to the left. With the type wheel in its present position, numerals, punctuation marks and other special characters may now be printed through the operation of the distributing and selecting mechanisms in a manner similar to that previously described in connection with the selection and printing of the character D.

Unshift.

When the type wheel is in a position for printing numerals, punctuation marks and other special characters and it is desired to unshift the type wheel from upper case to lower case, it is necessary that a special group of impulses be transmitted in a manner similar to that described in connection with the transmission of the impulses designating the character D for operating the distributing and selecting mechanisms to cause the alignment of one of the series of auxiliary balls carried in the discs 40 to 44, inclusive. The alignment of the balls to form a rigid operating connection selects the pin 137 individual to the pull bar 134 for causing this pull bar to be moved to a position where the notch thereof will be engaged by the universal bar 140 upon the

operation of the eccentric 141. When the pull bar 134 is moved, operating member 162 is likewise moved for causing the movement of a Y-shaped portion 161, of member 162, which has its arms, as shown in Fig. 11, on the upper and end side of the shaft 130 and in operative relation with the collar 160. The movement of the Y-shaped member 161 causes the movement of the shaft 130 to the right to a position where the pivoted member 158 again engages a surface of the collar 156 for holding the shaft 130 together with the type wheel 70 in a position such that the letters of the alphabet are in a printing position.

Carriage return.

Mention has already been made of the manner in which the type wheel and printing mechanism is moved from left to right step by step for line printing. When a full line has been printed or when it is desired to return the two carriages to the left to commence a new line, a group of selecting impulses is transmitted over the line to cause the operation of the distributing and translating mechanisms to select one of the auxiliary pull bars through the action of one of the pins 137. In this particular case the pull bar 133 will be moved upon the movement of the universal member 140. Attached to the pull bar 133 at its free end opposite to that near which the notch thereof is cut, is a rotatable member 163. This rotatable member 163 has a portion thereof formed in the arc of a circle and in its periphery there are cut two notches of different depths. When the rotatable member 163 is moved by the action of the pull bar 133, the operating pawl 121 and the holding pawl 122, which, as previously described, engage the ratchet wheel 120 for causing the movement of the type wheel from left to right to provide spacing between words, are caused to disengage the teeth of the ratchet wheel 120. With the pawls 121 and 122 out of engagement with the ratchet wheel 120, the shafts 129 and 130, upon which the type wheel carriage and the printing mechanism carriage are mounted, will be caused to rotate under the action of a spring 119 in a direction such that the respective carriages will be returned to the extreme left hand position for the commencement of a new line of printing. In order that the holding pawl 122 will not engage the teeth of the ratchet wheel 120 until the type wheel and printing mechanism carriages are returned to their normal starting position, a holding pawl 164 engages the shallower notch in the periphery of the rotatable member, thus preventing the restoration of the rotatable member 163 to its normal position until after the ratchet wheel 120 has been advanced upon the printing of the first char-

acter after the respective carriages have been returned to their normal starting position.

Although the invention has been shown and described as applied to a particular type of printing telegraph receiving printer, it is obvious that variations may be made without departing from the spirit and scope of the present invention.

What is claimed is:

1. In a type wheel arresting mechanism, a plurality of movable members, means for setting said members in predetermined combinations, and means loosely supported by said members and effective upon the movement thereof to form a rigid stop at various positions for said type wheel.

2. In a type wheel arresting mechanism, a plurality of independently movable elements selectively operated, means for setting said elements in predetermined combinations, and a plurality of elemental stop members loosely carried by each of said elements and aligned by the setting of said elements to form a rigid stop for said type wheel.

3. In a receiving telegraph printer, a shaft, a type wheel mounted on said shaft, means for arresting said type wheel shaft in any one of a plurality of positions comprising a plurality of independently movable plates each provided with a plurality of transverse openings, elemental stop members carried in said openings, and means controlled by line current impulses for selectively moving said plates to bring a desired series of elemental stop member into alignment to form a rigid stop whereby said type wheel is arrested in the desired printing position.

4. In combination, a plurality of revolvable and horizontally movable selecting members arranged to occupy either of two positions, means having a natural period of motion for controlling the rotation of said members, a locking vane for retaining said members in their actuated position, and an electromagnet having an armature with a beveled extension for causing said selecting members upon their rotation by said rotating means to be deflected to one side or the other of said locking vane depending on the energization of said electromagnet.

5. In a printing telegraph receiving printer operative on the start-stop principle, a plurality of revolvable and horizontally movable selecting elements, means having a natural period of motion for controlling the rotation of said selecting elements, and means responsive to a starting impulse for directly releasing said rotation controlling means and responsive to character selecting impulses for determining the position taken by said selecting elements upon their rotation.

6. In a printing telegraph receiver, a plurality of selecting elements capable of being

- revolved through a complete circular path arranged to occupy either of two positions, means responsive to line current impulses for determining the position taken by said selecting elements, and means for rotating said elements step by step in timed relation with said line current impulses for permitting the positioning of said elements in accordance with such line current impulses.
7. In a printing telegraph receiver, a plurality of selecting elements capable of being revolved through a complete circular path arranged to occupy either of two operative positions, means responsive to line current impulses for causing the positioning of said selecting elements into one or the other of their operative positions, a balance and escapement mechanism operative in time relation with the line current impulses for controlling the movement of said elements step by step to cause the setting thereof sequentially in accordance with the actuation of said first recited means.
8. In a printing telegraph receiver, a series of type, combination selecting mechanism, printing mechanism, auxiliary function mechanism, two power driven clutches means controlled by one of said clutches to move a selected type to printing position, and means controlled by the second clutch to operate in a single continuous revolution the selecting mechanism, the printing mechanism and the auxiliary function mechanism.
9. In a printing telegraph receiver, character type, character selecting mechanism, means to set the character selecting mechanism according to the character to be selected, means comprising a single power operated clutch to move the selected character type to printing position, and means comprising a second clutch operated once for each recording operation to set the character selecting mechanism and to operate the printing mechanism.
10. In a printing telegraph receiver, selecting mechanism comprising a plurality of selectable elements, a single selecting magnet responsive to line current impulses for positioning said elements into one of two operative positions, translating mechanism positioned in accordance with the operation of said selecting elements, character carrying means, means controlled by said translating mechanism for causing the positioning of said character carrying means in accordance with the setting of said selecting elements, and means responsive following the positioning of said character carrying means for causing a slight angular movement thereof to bring the desired character into accurate alignment with a printing mechanism.
11. In a printing telegraph receiver, a plurality of revolvable and horizontally
- movable selecting elements, means for positioning said selecting elements in accordance with line current impulses, translating mechanism controlled by said selecting elements comprising a plurality of members having a plurality of apertures, spherical members positioned in each of said apertures, a type wheel normally tending to rotate, and means for arresting the rotation of said type wheel upon the alignment of the spherical members carried by said plates in accordance with the operation of said selecting mechanism to bring the desired character into a printing position.
12. In a printing telegraph receiver, a plurality of revolvable and horizontally movable selecting elements, means for positioning said selecting elements in accordance with line current impulses, translating mechanism controlled by said selecting elements comprising a plurality of members having a plurality of apertures, spherical members positioned in each of said apertures, a type wheel normally tending to rotate, means for arresting the rotation of said type wheel upon the alignment of the spherical members carried by said plates in accordance with the operation of said selecting mechanism to bring the desired character into a printing position, and means operated following the positioning of the type wheel for effecting the printing of the desired character.
13. In a printing telegraph receiver, a plurality of circumferentially arranged selecting elements arranged to be positioned sequentially in accordance with line current impulses, translating mechanism operated simultaneously due to the movement of said selecting elements, a type wheel normally tending to rotate, and means controlled by the setting of said translating mechanism for arresting the rotation of said type wheel to bring the desired character into printing position.
14. In a printing telegraph receiver, a plurality of selecting elements arranged to occupy either of two operative positions, means for rotating said elements, means responsive to line current impulses for setting said elements upon their rotation sequentially, a plurality of operating elements normally tending to rotate, and means operated following the setting of said selecting elements for releasing said operating elements for rotation, said operating elements being arranged to control the printing and necessary auxiliary functions.
15. In a printing telegraph receiver, a plurality of revolvable and horizontally movable selecting elements arranged to occupy either of two positions, a single selecting magnet responsive to line current impulses for effecting the positioning of said elements into one or the other of their oper-

- ative positions, a battery of cams normally tending to rotate by power communicated thereto from a continuously rotating motor through a friction clutch, said cams being arranged to control the printing and the necessary auxiliary functions, and means operated following the setting of the selecting elements for permitting the rotation of said battery of cams.
16. In a printing telegraph receiver, a plurality of character selecting members, a plurality of auxiliary selecting members, means for selecting both groups of said members comprising a plurality of plates having apertures therein, spherical members fitted in said apertures for mechanically locking said plates, means controlled by line current impulses for positioning said plates to align predetermined ones of said spherical members, and all mechanical means operated due to the alignment of said spherical members for positioning one of said auxiliary selecting members for operation.
17. In a printing telegraph receiver, a plurality of auxiliary selecting members, means for selecting said members comprising a plurality of plates having apertures therein, spherical members fitted in said apertures for mechanically locking said plates, means controlled by line current impulses for positioning said plates to align predetermined ones of said spherical members, all mechanical means operated due to the alignment of said spherical members for positioning one of said auxiliary selecting members for operation, and means for operating the conditioned auxiliary member.
18. In a printing telegraph receiver, a type wheel and a printing mechanism, means for advancing said type wheel and printing mechanism step by step for character spacing, means for returning said type wheel and printing mechanism to their normal position for the commencement of a new line of printing comprising a plurality of plates having apertures therein, spherical members fitted in said apertures, means controlled by line current impulses for positioning said plates to align predetermined ones of said spherical members, a plurality of auxiliary selecting members and means operated by the alignment of said spherical members for conditioning one of said auxiliary selecting members for operation, said type wheel and printing mechanism being restored to their normal position following the conditioning of one of said auxiliary selecting members.
19. In a printing telegraph receiver, a type wheel and a printing mechanism, means for advancing said type wheel and printing mechanism step by step for character spacing, means for returning said type wheel and printing mechanism to their normal position for the commencement of a new line of printing comprising a plurality of plates having apertures therein, spherical members fitted in said apertures, means controlled by line current impulses for positioning said plates to align predetermined ones of said spherical members, a plurality of auxiliary selecting members, a plurality of plates having apertures therein, spherical members fitted in said apertures, means controlled by line current impulses for positioning said plates to align predetermined ones of said spherical members, means operated by the alignment of said spherical members for conditioning one of said auxiliary selecting members for operation, said type wheel and printing mechanism being restored to their normal position following the conditioning of one of said auxiliary selecting members.
20. In a printing telegraph receiver, a movable type carrying mechanism and a stationary platen, means for rotating said platen for positioning an unprinted area of the printing medium before the type carrying mechanism comprising a plurality of plates having apertures therein, spherical members fitted in said apertures, means controlled by line current impulses for positioning said plates to aligned predetermined ones of said spherical members, and means operated by the alignment of said spherical members for conditioning one of said auxiliary selecting members for operation, said platen being rotated for positioning an unprinted area of the printing medium before the type carrying mechanism following the conditioning of said auxiliary selecting member for operation.
21. In a printing telegraph receiver, a movable type carrying mechanism and a stationary platen, means for rotating said platen for positioning an unprinted area of the printing medium before the type carrying mechanism comprising a plurality of plates having apertures therein, spherical members fitted in said apertures, means controlled by line current impulses for positioning said plates to align predetermined ones of said spherical members, means operated by the alignment of said spherical members for conditioning one of said auxiliary selecting members for operation, and means operated following the conditioning of one of said auxiliary selecting members for operation for operating the conditioned auxiliary selecting member to effect the rotation of said platen to bring an unprinted area of the printing medium before the type carrying mechanism.
22. In a printing telegraph receiver, a movable type carrying mechanism and a stationary platen, means for rotating said platen for positioning an unprinted area of the printing medium before the type carrying mechanism comprising a plurality of plates

having apertures therein, spherical members fitted in said apertures, means controlled by line current impulses for positioning said plates to align predetermined ones of said spherical members, means operated by the alignment of said spherical members for conditioning one of said auxiliary selecting members for operation, a pawl and ratchet mechanism associated with said platen, and means for operating the conditioned auxiliary selecting member to cause the operation of said pawl for advancing said ratchet wheel.

23. In a printing telegraph receiver, a type wheel having two rows of characters arranged thereon, means for shifting said type wheel to bring either of said rows of characters into a printing position comprising a plurality of plates having apertures therein, an auxiliary selecting member individual to each of said plates, spherical members fitted in the apertures of said plates, means controlled by line current impulses for positioning said plates to align predetermined ones of said spherical members, means operated by the alignment of said spherical members for conditioning one of said auxiliary selecting members for operation, and means for operating the conditioned auxiliary selecting member for altering the position of said type wheel to bring the other row of characters into a printing position.

24. In a printing telegraph receiver, a type wheel having two rows of characters arranged thereon, means for shifting said type wheel to bring either of said rows of characters into a printing position comprising a plurality of plates having apertures therein, an auxiliary selecting member individual to each of said plates, spherical members fitted in the apertures of said plates, means controlled by line current impulses for positioning said plates to align predetermined ones of said spherical members, means operated by the alignment of said spherical members for conditioning one of said auxiliary selecting members for operation, means for operating the conditioned auxiliary selecting member for altering the position of said type wheel to bring the other row of characters into a printing position, and means controlled by another of said auxiliary selecting members for effect-

ing the movement of said type wheel to its normal position. 55

25. In a printing telegraph receiver operative on the start-stop principle, a plurality of revolvable and horizontally movable selecting elements, escapement means associated with said selecting elements to control their rate of rotation, and means responsive to a starting impulse for releasing said controlling means and responsive to character selecting impulses for determining the position taken by said selecting elements upon 60 their rotation. 65

26. In a telegraph receiver, recording mechanism comprising a recording member having thereon a group of designations to be recorded, a translating mechanism comprising a group of movable members, a series of movable elements mounted in each of movable members for locking said members together means controlled by the alignment of different combinations of movable elements to select the designation to be recorded according to the setting of said movable members. 70 75

27. In a printing telegraph receiver, a member carrying a plurality of recording designations, a translating mechanism, comprising a plurality of movable members, each having a plurality of apertures, members positioned in each of said apertures for locking said members together, means to move said movable members to have varying relations to one another, means controlled by the members in said apertures to select one of said recording designations according to the position of said movable members, and means to record the selected recording designation. 80 85 90

28. In a printing telegraph receiver, a type wheel, a combination device, auxiliary function mechanism, operating links individual to each function, means to control the printing position of the type wheel by the setting of the combination device, and means to control the selection of the auxiliary function links directly by the same combination mechanism. 95 100

In witness whereof, I hereunto subscribe my name this 28th day of December A. D., 1922.

LOUIS M. POTTS.
